(57) **CLAIM**

The ornamental design for a magazine holder, as shown and described.

DESCRIPTION

FIG. 1 is a perspective view of a magazine holder of our design;

FIG. 2 is a front elevational view thereof;

FIG. 3 is a rear elevational view thereof;

FIG. 4 is an elevational view of one side thereof, the opposite side being a mirror image thereof;

FIG. 5 is a top plan view thereof; and,

FIG. 6 is a bottom plan view thereof.

The broken line showing of paper in FIG. 1 is for illustrative purposes only and forms no part of the claimed design.
